UNITED STATES PATENT OFFICE.

GEORGE H. AUSTIN, OF READING, MASSACHUSETTS, ASSIGNOR, BY MESNE ASSIGNMENTS, TO SAMUEL WARD MANUFACTURING COMPANY, OF BOSTON, MASSACHUSETTS, A CORPORATION OF MASSACHUSETTS.

BOOKBINDING MACHINE.

Application filed May 27, 1924. Serial No. 716,145.

The object of this invention is the construction of substantially automatic means for applying fabric or leather to the boards designed to form the covers for books; and 5 the particular function which I am seeking to accomplish is that of folding the fabric or leather over the edges of the boards, especially where the same have rounded corners.

10 To this end I provide a mold having a suction-bottom upon which the cover and fabric are laid, the suction-bottom or plate then descending a short distance to turn the projecting edges of the fabric vertically upward; then the walls of the mold move 15 inward and fold the fabric edges over onto the cover, followed by a downward pressure upon these walls to cause the fabric edges to adhere to the cover, the fabric having previously been gummed.

In the drawings forming part of this specification, Fig. 1 is a plan view of the mold, parts thereof being broken away and in section. Fig. 2 is a sectional elevation on the irregular line 2—2, in Fig. 1. Fig. 3 is a side elevation of the machine, a part being broken away and in section. Fig. 4 is a plan view of the plunger. Fig. 5 is a sectional detail elevation on a larger scale showing 20 the fingers for acting upon the rounded corners of the covers. Fig. 6 is a plan view of the under side of the two superposed fingers. Fig. 7 is a sectional detail elevation of one 25 of the movable side walls of the mold and its operative mechanism.

As shown in Figs. 1 and 2, the mold comprises a base 1 centrally recessed, as at 2, to fit the book cover for which the machine is designed. Vertically movable within this 40 recess is a vacuum bottom or floor consisting of a thin chamber 3 whose top plate 4 is perforated around its margin, as at 5, and which is yieldingly retained in its uppermost position by springs 6. A tube 7 opening through the bottom plate 9 and vertically movable in the base 1, is connected by means of a rubber tube 10 to a suitable suction pump for exhausting the air in the chamber 3; and a yoke 11 attached to the 45 tube just below the base 1 is connected with a treadle or other means for lowering the chamber or floor.

At each end of the mold is a slidable block

12 composing an end wall for the mold, and at each side is a similar side wall 13, the 55 only difference being one of dimension. For sliding the blocks 12 and 13 inward, each is formed with spaced holes 14 provided with antifriction rolls 15 at the ends facing the recess 2; and a plunger 16 reciprocative 60 above the mold has a lug 17 disposed to enter each hole 14, each lug having a beveled end 19 for engaging the antifriction rolls 15 and thereby urging all the blocks 12 and 13 a 65 suitable distance inward.

For retracting these blocks, the base 1 has holes drilled therein close to the lateral sides of the blocks, and cutting through the vertical faces of the corner pieces 20, as at 21 in Fig. 1, and pressure springs 22 are 70 located in these holes to press against pins 23 projecting from the blocks. A screw plug 24 closes the outer end of each hole and also serves as a stop, by its engagement with a pin 23, to limit the outward play of the 75 blocks.

A plate 25 secured to the corner pieces 20 and resting lightly upon the blocks 12, 13, serves to retain the latter in the slide-ways 80 provided therefor.

As the covers are of the type having rounded corners, I provide narrow slides 26 and 27 for each corner of the mold, which are disposed at an angle of 45°, as shown in Fig. 1, the two being shown in Fig. 5. 85 The lower slide 27 is about equal in thickness to the cover and its fabric or leather facing, and has its inner end concaved to fit the rounded corner of the cover, as shown in Fig. 6. This slide 27 is not moved positively, but is moved by means of a spring 29 connected with the upper slide 26, which is actuated by a lug 30 depending from the plunger 16 similar to those above described but narrower to enter the narrow slot 31 in the slide. A tension spring 32 retracts the slide 26, and the pins 33, 34 cause the under slide to be simultaneously retracted. A screw 35 in the lug 36 limits the retraction of the upper slide.

The inner end of each upper slide is not rounded, but is given a right angled recess, as at 37 in Fig. 1.

The parts are so adjusted that the blocks 12 and 13 are moved inward a trifle earlier 105 in order that the ends of the upper slides

26 shall fall behind the fingers 38 projecting from the blocks and formed by the beveled recesses 39. These fingers are necessary in order that the entire fabric edges equal in 5 length to the blocks including the fingers 38 shall be met and forced downward upon the cover, while the recesses 39 are necessary in order to provide room for the ends of the slides 26 since otherwise the ends or prongs 10 of the latter would strike the sides of the blocks 12 and be prevented from passing in over the cover after the latter has been depressed.

In the bottom of the recess 2 are located 15 two wedges 40 upon which the under plate of the suction chamber 3 is seated when drawn downward by the pull of the straps 11 on the tube 7. By longitudinally adjusting these wedges, the suction chamber and 20 hence the top plate 4 are raised or lowered to accommodate different thicknesses of cover and of fabric or leather. The illustrated means for adjusting these wedges consists of a knurled headed screw 41 for 25 each, held from longitudinal play by any suitable means, and engaging a nut 42 held in jaws at an end of a wedge 40.

The operation of the machine is as follows: A pair of covers having been properly 30 located upon a gummed sheet of fabric or leather, with the edges of the latter extending uniformly beyond the cover's edges for about three-eighths of an inch all around, the same are placed upon the top plate 4 35 with the edges of the fabric coinciding with the inner edges of the plate 25. The vacuum chamber 3 is then put into communication with the suction pump thereby drawing the cover tightly down upon the plate 4, and 40 immediately after the chamber is pulled mechanically downward to its limit drawing the fabric and cover down with it. The surrounding walls of the mold, consisting of the blocks 12 and 13, as the fabric descends, 45 turns the latter's edges vertically upward. Following this, the blocks 12, 13 move inward and then the slides 26, 27; the slides 27 coming at rest against the rounded corners of the cover, thereby ensuring them 50 against wrinkles, while the blocks 12, 13

and the slides 26 pass on for a short distance folding the fabric edges down upon the cover. This alone is insufficient to perfectly paste the fabric edges to the cover. To do this, the plunger 16 is provided with a pressure block 45 equal in horizontal dimensions to slightly less than the opening through the plate 25; which block at the end of the plunger's downward stroke, descends upon the inner extremes of the blocks 12, 13 and slides 26 and by its action thereon causes them to strongly press the turned fabric edges into perfect engagement with the surface of the cover.

The air being shut off and the plunger suffered to rise, followed by the vacuum chamber, the completed cover is removed and another gummed one put in place. It is well not to have the blocks 12, 13 and the slides 26 taper somewhat; in other words, be thinner toward their outer extremes, in order that as the pressure block 45 descends upon their inner extremes, the latter can rock downward and so make sure of effecting the proper action upon the fabric edges.

In Figs. 5 and 7, the fabric edges 46 are shown as only partially flattened down upon the cover 47, since the blocks 12, 13 and slides 26 have not yet completed their inward travel.

What I claim as my invention is:

1. In a machine for applying fabric and the like to book covers, an air tight chamber having a flat top plate provided with a series of closely disposed holes adjacent its edges, and means for temporarily creating a vacuum in said chamber and thereby tightly holding the fabric and cover upon said plate while the edges of the fabric are folded over upon the cover.

2. In a machine for applying fabric and the like to covers, a mold, a vertically movable bottom plate therein, and supports for adjustably limiting the descent of said plate, said supports consisting of wedges each having a screw for its longitudinal adjustment.

In testimony that I claim the foregoing invention, I have hereunto set my hand this 26th day of May, 1924.

GEORGE H. AUSTIN.
